US0D1047052S

(12) **United States Design Patent** (10) **Patent No.:** **US D1,047,052 S**
(45) **Date of Patent:** **** Oct. 15, 2024**

(54) **STRAP**

(71) Applicant: **Nite Ize, Inc.**, Boulder, CO (US)

(72) Inventors: **Bowden Ormsbee**, Longmont, CO (US); **Dale Karacostas**, Boulder, CO (US)

(73) Assignee: **Nite Ize, Inc.**, Boulder, CO (US)

(**) Term: **15 Years**

(21) Appl. No.: **29/791,218**

(22) Filed: **Jan. 5, 2022**

(51) LOC (14) Cl. **21-02**

(52) U.S. Cl.

USPC **D21/774**; D30/152

(58) **Field of Classification Search**

USPC D2/627, 636-638; D3/215, 318, 327; D21/694, 774; D30/152; D8/356, D8/382-383, 394, 396, 499

(57) **CLAIM**

The ornamental design for the strap as shown and described.

DESCRIPTION

FIG. 1 shows a front perspective view of a strap; FIG. 2 shows a front view of the strap of FIG. 1; FIG. 3 shows a rear view of the strap of FIG. 1; FIG. 4 shows a right side view of the strap of FIG. 1; FIG. 5 shows a left side view of the strap of FIG. 1; FIG. 6 shows a top view of the strap of FIG. 1; and, FIG. 7 shows a bottom view of the strap of FIG. 1. The strap is shown with a symbolic break in its length. The appearance of any portion of the article between the break lines forms no part of the claimed design.

1 Claim, 4 Drawing Sheets
